UNITED STATES PATENT OFFICE.

ALBERT H. WEIS, OF NYACK, NEW YORK, ASSIGNOR TO LUCIUS N. LITTAUER, OF GLOVERSVILLE, NEW YORK.

RENEWABLE THROAT-PLATE FOR SEWING-MACHINES.

1,230,354.

Specification of Letters Patent. Patented June 19, 1917.

Application filed July 21, 1915. Serial No. 41,094.

To all whom it may concern:

Be it known that I, ALBERT H. WEIS, a citizen of the United States, residing at Nyack, in the county of Rockland and State of New York, have invented certain new and useful Improvements in Renewable Throat-Plates for Sewing-Machines, of which the following is a specification.

This invention relates to the throat plates 10 of sewing machines, one object of the invention being to provide a substantial throat plate especially well adapted to machines of the gang needle type and which can be cheaply manufactured and readily renewed 15 when it becomes worn, without disturbing the entire plate, and can also be interchanged with other forms of plates usable for different purposes, that is to say to accommodate different shapes of feed dogs or 20 to have the front portion thereof shaped so as to guide certain plies of goods to the right or the left as the case may be by means of the beveled portion at the front edge of the plate.

25 Throat plates as used for gang needle machines are necessarily of a large size, several times larger than the throat plates as used on ordinary machines. The manufacture of these large plates entails considerable 30 expense, since they must be accurately made, hardened and ground on top and bottom so as to be perfectly parallel and flat. This necessitates straightening after the hardening process and a percentage of them is lost 35 in the straightening process because of breakage. Then again though they are hardened, the needle holes soon become worn by use and the entire plate must be replaced by a new one. This is entirely done away 40 with in the present improvement, because the main throat plate may be made as usual but without the hardening and straightening or grinding, so that there are no losses in the manufacture thereof.

45 Moreover, it has been found in practice, with throat plates used on gang needle machines, that when the plate is of considerable size, especially on machines for stitching wide rows, the strain set up by the needles 50 penetrating the goods has a tendency to spring the plate so as to interfere with the stitching mechanism to properly form the stitches. Especially is this so in certain de-

signs of feeds where the bars of the throat plate are delicate, because the needles are 55 close to one another, so that it is necessary for portions of the feed dogs to extend between the needles, and therefore the plates quickly get out of shape in use. To overcome this it has been the practice to harden 60 and temper the plates. The difficulty in doing this is that the delicate bars or thin sections of the plate become harder than the other portions thereof, which results in considerable breakage because the plates sometimes warp in hardening or tempering and must be straightened. Then again they break easily under the working strain of 65 the needles.

To overcome these disadvantages I have 70 provided a removable and renewable top plate much smaller in size and thickness than the main plate so that it can be manufactured cheaply, and consequently the cost of renewal is greatly reduced and the life 75 of the plate is longer than that of plates as heretofore made, because stiffness is imparted to the plate and offers various advantages because these top plates can be 80 made to suit the various stitching operations, that is one substituted for the other for special purposes without changing the main plate, which was heretofore necessary. In short, with this improved renewable top plate the bottom or supporting plate need 85 not be hardened, and as the top plate is independent of or a separate piece from and much smaller than the bottom plate it can be made cheaply, as there is not the difficulty in hardening and tempering this small 90 plate that there is with a larger plate such as the throat plate itself. Even when the throat plates are hardened and tempered the continual passing of the goods over the same, particularly around the needle holes, 95 wears the plate and the edges of the needle holes become rounded, and frequently when a needle breaks by accident the plate is damaged beyond repair. This is all obviated with my improved renewable top plate, as 100 the top plate itself can be quickly and readily renewed. Moreover, this improved plate gives greater strength and support to the work.

Another important advantage of this improvement is that the top plate may be so

mounted as to be above the level of the cloth and slide plates, which gives free passage to the work past the stitching mechanism and is of special advantage on machines used 5 for lap seam felling shirts, overalls, etc., because the work as delivered from the folder is more on a central line with respect to the stitching position and it also gives freedom to the work around the presser foot and 10 feed.

In this type or class of machines raised plates have been used extensively, but so far as I am aware none have been of the detachable variety. Usually such plates are made 15 by reducing the thickness of the main plate around the stitching position. Others have been made by forcing or bending the metal upward, leaving a hollow space on the bottom thereof, both of which methods are expensive. 20

Another important feature of my improvement is that the extra thickness of the throat plate at and around the feed slots permits the extending portions of the feed 25 dog to operate very close to and substantially over the loopers, whereas heretofore with the thin plate the feed dog in its movement forward would strike the loopers and interfere with the stitch, but because of this 30 extra thickness the projecting ends of the feed may be made stronger and yet as the feed moves downward and forward it will have sufficient clearance over the top of the loopers so as not to interfere with the same. 35

The portion of the throat plate in front of the needles extends slightly to give strength to the plate at the front of the feed slots.

My improved throat plate has still another advantage, in that it may be cut away 40 practically up to the stitching line and a slide plate used to fill up the cut out portion upon which various attachments may be mounted, and as it is frequently necessary to have different attachments for the 45 various operations on each garment, by means of the present improvement several slide plates with their respective attachments may be placed in position one after the other to suit the character of work. All this can be accomplished very quickly, as there are 50 no screws or clamping devices necessary to hold the plate in position. Furthermore, by removing the slide the attachments are removed with it and free access to the stitching and feeding mechanism is had. 55

Another object of the invention is the provision of an improved throat plate constructed to properly retain for a certain period a looper thread strand without forming a loop or requiring the use of a take-up device to take up the extra thread of such a loop.

In the drawings accompanying and forming part of this specification, Figure 1 is a 60 perspective view of as much of a sewing ma-

chine as is deemed necessary to illustrate this improvement, and shows the needles and loopers, the cloth plate, the main and renewable throat plate, and also the slide plate in dotted lines with an attachment applied thereto; Fig. 2 is a detail perspective view showing the main throat plate and the top plate removed therefrom; Fig. 3 is an end view of the bottom and top throat plate looking in the direction of the arrow in Fig. 75 1; and Fig. 4 is a bottom view of the bottom throat plate, showing the feed slots, needle holes and slots leading therefrom to properly coöperate with the looper threads in the formation of the stitch. 80

The needle holder 1 carries the needles 2, and the loopers 3 coöoperating with the needles in the formation of the stitches are carried by the looper carrier 4. The cloth plate 5 is milled or recessed to receive the bottom 85 throat plate 6, which is secured to the cloth plate by the usual screws 7. I prefer to use screws and screw holes for attaching the plate which will provide a slight adjustment at right angles and parallel with the milled 90 or recessed surface of the cloth plate 5 to facilitate in lining up the needle holes in the throat plate with the needles. To accomplish this the holes in the plate may be enlarged as shown at 8 and the recess in the 95 cloth plate 5 be slightly larger than the throat plate 6, to permit its adjustment. The bottom plate 6 is provided with the usual feed slots 9, which may be of any form to suit the character of feed used, and the character of feed is usually designed to suit the 100 number of needles and the style of work for which the machine is to be used. For lap seam felling work it is desirable to have the feed slots extend up to and slightly in front of the needles, as at 10. The needle holes 11 for the needles are on the bottom 105 of the plate enlarged slightly, as at 12, to give clearance for the looper threads and a saw cut or groove 13 extends from each needle hole, this groove being located at one side thereof and enables a strand of the looper thread to be placed thereon as the looper moves backward in the formation of the stitch. Each groove has at one side a 110 substantially straight wall 12' and at its opposite side a wall terminating adjacent to the needle opening in a projection 12' shown herein as V-shaped, which extends in the plane of the plate and does not project 115 below the bottom surface of the plate. Heretofore pins, spreader bars, etc., have been used for the purpose of spreading and thereby forming a loop, but I have found in practice that the pins or spreader bars become 120 disarranged and the threads are apt to hook over the same so as to snag and break the thread. Moreover, the pins become worn, as there is but a very small portion of them 125 which coacts with the threads, and when they 130

are worn they do not perform their functions properly. This has been overcome by the present improvement, as the grooves are of considerable length, so that the thread is retained therein during the entire forward movement of the looper and there is no possibility of the thread snagging, as there is no portion upon which the thread could catch or hook and there are no projections below the bottom of the throat plate for the looper to interfere with, and consequently the thread is more accurately handled thereby.

In the present improvement as above stated, the strand or thread of the looper is held or retained during a certain part of the movement of the looper and this results in holding or retaining one strand of the looper thread to one side of the needle hole, while the needle is descending to enter between it and the looper body. In other words, the present strand retaining device does not act in any similar way to pins or projections extending below the throat plate, which necessarily spread the thread and form a loop, and so require a take-up device of some kind to take up this extra thread loop when it is cast from the pins. In the present improvement no take-up device is necessary or required to take up the looper thread for the reason that there is no loop formed by this retaining device. As the looper moves backward and laterally the thread is drawn from the retaining device in proportion to the movement of the looper, so that therefore there is no excess amount of thread or a loop to be taken up.

In the operation of the needles and the loopers, the looper thread of each looper is carried forward as the looper enters the needle loop. The loopers move sidewise and as these movements take place the strand of each looper thread extending from the forward eye of the looper to the previous stitch passes into the groove or saw cut 13 so as to be held or retained at one side of the needle hole as the needle is descending to take a loop of thread from the looper.

Threaded holes 24 are provided in the bottom or main plate 6 for attaching the top plate 15, which has similar holes 16 to receive screws. This removable and renewable top plate 15 has feed slots 17 corresponding with the feed slots 9 and 10 of the bottom plate and is also provided with needle slots or holes 18 corresponding with the needle holes 11 of the bottom plate. The front edge of the top plate is usually beveled, as at 19, from the edge up to the needle holes, either from the right or left side, leaving a vertical wall 20 in line with either the right or left needles to act as a guide for the bottom edge of the work to control it while it is fed to the stitching position, so that the needle will stitch accurately along

the edge thereof. It is obvious that the front edge of these top plates may be grooved, slotted or otherwise shaped so as to guide the work or seams as the case may be. The throat plate 6 has an extending portion 21 in front of the needles and is cut away, as at 22 at each side thereof and has extending ends 23. The removable slide plate 24 fits into the irregular shaped opening formed in the front of the plate 6 indicated by the parts 23, 22 and 21. The slide plate rests on the rabbeted part 25 of the cloth plate 5 and is provided with a plate spring, (not shown), on the underside thereof to rest against the bottom of the cloth plate and hold the slide plate 24 in position. This slide plate 24 may carry a folder or other attachment 26. These are sometimes secured to the bottom for running a strip underneath the garment. The removal of this slide plate affords quick and easy access to the mechanism below the cloth plate.

The various details may be more or less changed without departing from the spirit or scope of the present improvement.

I claim as my invention:

1. A throat plate comprising a bottom plate and a renewable one piece top plate of less size than said bottom plate and resting throughout its area on the top of said bottom plate, said bottom and top plates having one or more registering needle openings and each of said plates having integral bars forming, when juxtaposed, registering feed slots.

2. A throat plate comprising a bottom plate and a renewable one piece top plate of less size than said bottom plate and resting throughout its area on the top surface of said bottom plate to project above the same, said bottom and top plates having one or more registering needle openings.

3. A throat plate comprising a bottom plate and a renewable one piece hardened top plate smaller than said bottom plate and resting throughout its area on the top of said bottom plate, said top and bottom plates having one or more registering needle openings and each of said plates having integral bars forming, when juxtaposed, registering feed slots.

4. A throat plate comprising a bottom plate and a renewable top plate, said top and bottom plates having one or more registering needle openings, each of said needle openings of the bottom plate having a groove extending therefrom at one side thereof and forming a looper thread strand retainer to retain the strand so that the needle can pass between it and the looper.

5. A throat plate comprising a bottom plate and a renewable top plate raised above the top surface of said bottom plate, said top and bottom plates having one or more registering needle openings, each of said

- needle openings of the bottom plate having a groove extending therefrom at one side thereof and forming a looper thread strand retainer to retain the strand so that the needle can pass between it and the looper.
- 5 6. A throat plate comprising a bottom plate and a renewable hardened top plate, said top and bottom plates having one or more registering needle openings, each of said needle openings of the bottom plate having a groove extending therefrom at one side thereof and forming a looper thread strand retainer to retain the strand so that the needle can pass between it and the looper.
- 10 7. A throat plate comprising a bottom plate and a top plate, the top plate being considerably smaller than the bottom plate, said top and bottom plates having one or more registering needle openings, each of said needle openings of the bottom plate having a groove extending therefrom at one side thereof and forming a looper thread strand retainer to retain the strand so that the needle can pass between it and the looper.
- 15 8. A throat plate comprising a bottom plate and a renewable hardened top plate smaller than said bottom plate and raised above said bottom plate, said top and bottom plates having one or more registering needle openings, each of said needle openings of the bottom plate having a groove extending therefrom at one side thereof and forming a looper thread strand retainer to retain the strand so that the needle can pass between it and the looper.
- 20 9. A throat plate comprising a bottom plate and a renewable hardened top plate of smaller size than said bottom plate and raised above said bottom plate, said bottom plate and top plate having one or more registering feed slots and one or more registering needle openings, a part of each of said needle openings having a groove extending therefrom at one side thereof and forming a looper thread strand retainer to retain the strand so that the needle can pass between it and the looper.
- 25 10. A throat plate having a needle opening provided with a groove extending therefrom and only partially through the plate and forming adjacent to its underside a looper thread strand retainer.
- 30 11. A throat plate having a needle opening, said plate having on its underside a groove extending from said needle opening toward the front of said plate and only partially through the plate and forming adjacent to the underside of the plate a looper thread strand retainer.
- 35 12. A two-part throat plate having one or more needle openings therein, each of said needle openings having a groove extending therefrom and located in one of said plate parts and forming a looper thread strand retainer to retain the strand so that the needle can pass between it and the looper.
- 40 13. A throat plate having a needle opening and a groove located in said plate and forming a projecting at the underside of said plate for retaining a looper thread strand so that the needle can pass between it and the looper.
- 45 14. A throat plate having a needle opening, and means integrally formed in the plate to extend in the plane of the plate above the bottom surface thereof for retaining a looper thread strand so that the needle can pass between said strand and the looper.
- 50 15. A two-part throat plate comprising a bottom plate and a renewable top plate having one or more registering needle openings and feed dog openings, and means carried by the bottom plate for retaining a looper thread strand so that the needle can pass between it and the looper.
- 55 16. A two-part throat plate comprising a bottom plate and a renewable top plate having one or more registering needle openings, and means located below the underside of the top plate and above the underside of the bottom plate for retaining a looper thread strand and formed by a groove at one side and extending forwardly of and communicating with a needle opening.
- 60 17. A throat plate comprising a two-part bottom plate, one part shiftable relatively to the other and one of said parts having a renewable top plate.
- 65 18. A throat plate comprising a two-part bottom plate, one part slidable relatively to the other, the fixed part thereof having a renewable top plate.
- 70 19. The combination with the cloth plate of a sewing machine, of a two-part bottom plate, one part slidable relatively to the other, the non-slid part thereof having a renewable and hardened top plate raised above the bottom plate.
- 75 20. A throat plate comprising a two-part bottom plate, one part shiftable relatively to the other and one of said parts having a renewable top plate, said top plate and bottom plate having one or more needle openings and looper thread strand retaining means.
- 80 21. A throat plate comprising a two-part bottom plate, comprising a fixed plate and a plate slidable relatively thereto, the fixed plate having a renewable top plate, said top plate and fixed plate having one or more needle openings and looper thread strand retaining means communicating therewith.
- 85 22. A throat plate comprising a two-part bottom plate, comprising a stationary plate and a plate slidable relatively thereto, the stationary plate having a renewable and hardened top plate raised above it and said top plate and stationary plate having one

- or more needle openings and looper thread strand retaining means communicating therewith.
23. The combination with the cloth plate 5 of a sewing machine, of a two-part bottom plate, one part slidably relatively to the other part, said other part thereof having a renewable and hardened top plate raised above it, said top plate and its bottom plate 10 having registering feed slots and one or more needle openings, each of said needle openings having communicating therewith at one side and extending forwardly thereof a groove forming a looper thread strand retaining means.
24. A throat plate having a needle opening and a groove extending partway only through the plate and communicating with
- 20 said needle opening and forming a looper thread strand retainer.
25. A throat plate having a needle opening, and means integrally formed in the plate to extend in the plane of the plate above the bottom surface thereof for retaining a looper thread strand to permit the 25 needle to pass between said strand and the looper and comprising a groove at one side of the needle opening, one of the walls of said groove terminating adjacent to the needle opening in a substantially V-shaped 30 projection.

Signed at Nyack, in the county of Rockland and State of New York, this 15th day of July, 1915.
